UNITED STATES PATENT OFFICE.

HARRY W. PUGH, OF NEW YORK, N. Y., AND JAMES A. WOTTON, OF MONTCLAIR, NEW JERSEY, ASSIGNEES TO WESTERN ELECTRIC COMPANY, INCORPORATED, OF NEW YORK, N. Y., A CORPORATION OF NEW YORK.

ADAPTER FOR TELEPHONE CALLING DEVICES.

1,387,945.

Specification of Letters Patent. Patented Aug. 16, 1921.

Application filed November 11, 1919. Serial No. 337,358.

To all whom it may concern:

Be it known that we, HARRY W. PUGH and JAMES A. WOTTON, citizens of the United States, residing at New York, in the county 5 of Bronx and State of New York, and at Montclair, in the county of Essex and State of New Jersey, respectively, have invented certain new and useful Improvements in Adapters for Telephone Calling Devices, of 10 which the following is a full, clear, concise, and exact description.

This invention relates to adapters for calling devices and transmitters, and more particularly to an adapter providing means for 15 assembling together a calling device and a telephone transmitter into a self-contained unit which may be readily attached to a subscriber's telephone instrument.

Its object is an adapter whereby a calling 20 device and a transmitter may be readily attached to a wall type subscriber's telephone instrument, without the necessity of making any additional holes or otherwise defacing the telephone instrument.

25 This adapter is particularly intended for application to telephone instruments connecting with central offices which have been reequipped and transformed from manual operation to automatic operation.

30 When a previously manually operated telephone central office is reequipped for automatic operation, it is necessary to equip each subscriber's telephone instrument connecting with that office, with a calling device 35 such as that described in United States Patent No. 1161854 to O. F. Forsberg which, if mounted directly on the face of a wall type instrument, necessitates making a hole therein, at or near the point where the calling 40 device is to be mounted in order to pass the wires connecting with the calling device to the interior of the instrument, or, as an alternative, to run the wires from the calling device along the face of the instrument to 45 the opening at the rear of the transmitter, through which the wires connecting with the transmitter are passed to the interior of the instrument. This latter method would result in an unsightly appearance incompatible with good telephone practice.

50 It is, of course, desirable in attaching calling devices, that the necessity of making additional holes in the subscribers' telephone instruments be obviated and furthermore, on

some types of subscribers' wall type instruments it is impracticable to bring the connecting wires for the calling device through the face of the instrument at the particular point where it is desired to attach the dial, on account of interference by apparatus inside the set. This is especially true of some types of coin collecting telephones, wherein any additional wires which might be passed through the face of the instrument would be likely to interfere with the coin chute 65 therein.

This invention provides an adapter combining in one piece, means whereby a calling device can be mounted on a subscriber's telephone instrument of the wall type without the necessity of making any additional holes in said instruments, means for mounting a transmitter on said subscriber's instrument, and an inclosed conduit for the conductors leading from the telephone set to 75 the transmitter and calling device.

Referring to the drawings, Figure 1 is a side elevation and Fig. 2 a front elevation showing the adapter with a calling device and transmitter attached thereto and mounted on the face of a telephone wall type instrument. 1 is the adapter, 2 is the calling device, 3 the transmitter, and 4 the telephone box. Fig. 3 is a perspective view of the adapter in which 5 is a channel forming a 80 conduit for the conductor from the calling device to an opening in the face of the telephone box situated at the rear of the transmitter through which the conductors from both the calling device and the transmitter 85 are passed to the interior of the telephone box. 7 and 8 are screw holes for attaching the adapter to the face of the telephone box. 9 is an opening provided for passing the transmitter cord through the adapter to 90 the aforementioned opening in the face of the telephone box through which the cords pass to the interior thereof. 10, 11 and 12 are holes provided for attaching the calling device to the adapter, and 13 and 14 100 are lugs for attaching the transmitter to the adapter, lug 13 being shown with a part broken off in order to expose the opening 9.

What is claimed is:

1. In combination, a subscriber's telephone set including a transmitter, an adapter, a calling device attached to one end portion of said adapter, said transmitter mounted

on the other end portion thereof, and means for detachably mounting said adapter on said set.

2. In combination, a subscriber's telephone set including a transmitter, an adapter comprising a metal plate, a calling device attached to one end portion thereof, a channel integral with said adapter forming a conduit for conductors for said calling device, and means for detachably mounting said adapter on said set.

3. In combination, a subscriber's telephone set including a transmitter, an adapter comprising a formed metal plate, a calling

device attached to one end portion of said adapter, said transmitter mounted on the other end portion thereof, a channel integral with said adapter forming a continuous conduit from said calling device to a point at the rear of the transmitter, and means for detachably mounting said adapter on said set.

In witness whereof, we hereunto subscribe our names this 8th day of November, A. D. 1919.

HARRY W. PUGH.
JAMES A. WOTTON.
